UNITED STATES PATENT OFFICE

119,351

DESIGN FOR A TEXTILE FABRIC

Adrian Tabin, Chicago, Ill.

Application August 30, 1939, Serial No. 86,943

Term of patent 3½ years

To all whom it may concern:

Be it known that I, Adrian Tabin, a citizen of the United States, residing in Chicago, in the county of Cook and State of Illinois, have invented a new, original, and ornamental Design for a Textile Fabric, of which the following is a specification, reference being had to the accompanying drawing, forming a part thereof.

The figure is a plan view of a textile fabric showing my new design.

I claim:

The ornamental design for a textile fabric, as shown.

ADRIAN TABIN.
